Mason Fenwick Lawrence

ATTORNEY'S

UNITED STATES PATENT OFFICE.

JOHN A. BISHOP, OF CLEARWATER, FLORIDA.

FLUID-FUEL BURNER.

Application filed June 7, 1921. Serial No. 475,657.

To all whom it may concern:

Be it known that I, JOHN A. BISHOP, a citizen of the United States, residing at Clearwater, in the county of Pinellas and 5 State of Florida, have invented certain new and useful Improvements in Fluid-Fuel Burners; and I do hereby declare the following to be a full, clear, and exact description of the invention, such as will enable 10 others skilled in the art to which it appertains to make and use the same.

This invention relates to means for converting a liquid fuel into vapor or gas so that it may be completely burned.

15 The objects are to preheat the liquid fuel in the feed pipes or feed pipe so that it may be issued from the ejecting nozzle in a finely divided or vaporous condition; to provide a stream of air or steam adapted 20 to entrain the fuel immediately before it issues from the ejector nozzle; to cut off completely either the fuel or the air or steam or to regulate the proportional discharge of fuel and air and steam, and to 25 provide means for forcing the air or steam through the fuel pipe in order to remove any obstructions that may accumulate therein.

The invention consists in the combination 30 of a burner pipe adapted to be highly heated by the flame of the burning fuel, a fuel conductor adjacent said burner pipe adapted to be heated by transfer of heat therefrom, an ejector nozzle directed into the burner pipe, a needle valve for controlling 35 the fuel passing to the nozzle, a steam or air pipe in communication with the needle valve and nozzle, and controlling valves that may be manipulated so as to direct the steam or air through the heated 40 section of the fuel conductor or into the nozzle. It also consists of the several sub-combinations and elements more specifically set forth hereinafter, illustrated in the drawings and defined in the appended 45 claims.

In the accompanying drawings in which like reference numerals indicate like parts throughout the several views:

Figure 1 is a diagrammatic side elevation 50 of the complete apparatus;

Figure 2 is a section on the line 2—2 of Figure 1;

Figure 3 is an end elevation viewed from the left of Figure 1;

55 Figure 4 is a sectional view of the ejector

nozzle disclosing the valve for controlling the fuel and the air or steam.

In the drawings, 1 indicates the burner pipe which is preferably a section of cast iron pipe relatively heavy and large in 60 diameter with respect to the fuel pipe or conductor and intended to be susceptible of absorbing and giving off a large amount of heat; 2 is a fuel pipe or conductor adapted to conduct a liquid fuel, such as petroleum, 65 to a nozzle 10 that is directed into the front end 1^a of the burner pipe 1. The said fuel conductor pipe 2 is designed to be heated by contact with the flame of the ignited fuel issuing from nozzle 10 and by the 70 transfer of heat from burner pipe 1. In the particular construction shown the said fuel pipe extends in a loop, the entrance limb 3 of which lies close to one side of the pipe 1 and the other or exit limb 4 of 75 which lies close to the opposite side of said pipe 1. The bight of the loop preferably consists of a plurality of U's or bends extending in a vertical plane or in a plane which intersects the axis of the pipe 1, thus 80 producing a large heat absorbing or heat radiating surface approximating in extent the cross sectional area of the pipe 1 and therefore so placed that flame issuing from said pipe 1 contacts with it. The said 85 bends are designated 5 in the drawings and the ends thereof may be connected to the limbs 3 and 4 of the fuel pipe by elbows 6. A valve 7 is provided for controlling the 90 flow of fuel through the pipe 2 before it reaches the heated limb 3 in the immediate vicinity of burner pipe 1. The limb 4 of the fuel pipe is connected with a transverse section directed toward the center or axis of the pipe 1 adjacent the front end 1^a where it is connected to a cross to which 95 the before-mentioned nozzle is secured. The front end of the limb 4 may be tapped into an elbow 8, from which a transverse section of pipe 9 extends to a cross 11. Said 100 nozzle 12 is screwed into one arm 12 of the cross. The nozzle 10 has a flaring discharge mouth 13 communicating with a bore 10^a and a tapered valve seat 14 at the inner end 105 of the bore 10^a adapted to be closed by means of a taper end 15 of a needle valve 16 having a hollow end. Fuel flowing through the pipe 2 and into the cross 11 will be discharged past the valve seat 14 and out through the flaring nozzle 13 pro- 110

vided the taper end 15 of valve 16 is removed from its seat.

Threaded into the end 17 of the cross is a hollow plug 18, closed at its end, which 5 is connected to the section 19^a of the steam or air pipe 19 that is provided with a valve 20 in order to control the flow of air or steam into said hollow plug. Said hollow plug 18 is transversely drilled and threaded 10 at 21. The needle valve 16 is provided with a bore 22 extending from its extremity and terminating beyond an orifice 23 extending transversely through the stem of said needle valve. The needle valve stem is threaded 15 as shown at 24 and is screwed through the threaded opening 21 in the plug 18 so that the orifice 23 is in communication with the interior of the plug 18 throughout the longitudinal movements of the valve stem necessary to open and close communication 20 between the fuel conduit and the nozzle 10. The said needle valve is guided in a suitable gland or stuffing box 25 threaded into the end 26 of said cross 11.

25 By means of the construction last described it will be apparent that when the valve 20 is closed and the valve 16 opened fuel may flow freely through the cross 11 and out of the nozzle 10 without any admixture of steam or air. By opening the valve 16 any desired amount and opening the valve 20 steam or air may be forced out through the hollow stem of the valve 16 thereby entraining and mingling with the 30 fuel which is then ejected from the flaring mouth 13 of the nozzle 10 in a finely divided spray. Liquid fuel may thus be atomized or divided finely as may be necessary in order to bring the fuel into condition to be initially ignited. Valve 20 may be closed at any time after the pipe 1 and the heating section of the fuel conduit have been heated to such a degree that the fuel issues from the nozzle 10 in a gaseous or 35 vaporous condition. By closing the valve 16 and leaving the valve 20 open steam or air may be blown through the nozzle for any desired purpose, such as to clear away an obstruction.

50 In order to clean out the entire heating section of the burner pipe or conduit, which is subject to the more or less intense heat required to vaporize the fuel, a cross connection 27 having therein a valve 28 is branched from the steam or air pipe 19 to the fuel pipe 2. By closing the valve 20, opening the valves 16 and 28 and closing the valve 7, steam or air may be blown through the sections 3, 5 and 4 of the fuel 55 conduit, thus loosening any clogging material that may have accumulated in said pipes and forcing it out through the nozzle 10.

60 The apparatus described is particularly designed for burning liquid fuel such as the

petroleum fraction known as distillate, or other oils of like consistency. In starting the apparatus oil will be forced through the fuel pipe and out of the nozzle 10, mechanically broken up or atomized by the current 70 of steam or air forced through the hollow needle valve into said nozzle. The fuel is thus brought into so finely divided a condition that it may be ignited and burned, although at first the combustion will not be 75 complete. Continued burning of the vaporous fuel will soon heat the pipe 1 and the heating absorbing device 5 at the extremity 1^b of said pipe 1; the sections 3 and 4, 80 in substantial contact with the pipe 1, become heated by transfer from pipe 1 and the bends 5 by direct contact with the flame. The conduit will soon become so hot that oil therein will be heated to such a degree that it issues from the nozzle 10 as a gas or 85 vapor which may be completely consumed provided sufficient air is furnished for the purpose. As the pipe 1 is relatively large in cross section, sufficient air for combustion purposes will be drawn into the open end 90 1^a by the force of the stream of fuel issuing from the nozzle 10, which may be supplemented by air enveloping the burning gases after they have issued from the end 1^b of said pipe 1.

95 By the burner disclosed I have found that hydrocarbon oils may be brought into such a volatile condition that when ignited complete combustion is effected.

Having described my invention in the 100 form now best known to me what I claim and desire to secure by Letters Patent is:

1. A fuel conductor terminating in a nozzle, a valve seat in said nozzle, a needle valve provided with a taper ended stem 105 adapted to engage said valve seat, said needle valve having a central bore in communication with said nozzle, and a lateral opening into said bore, a hollow plug having a closed end and a transverse opening receiving the 110 perforated portion of the stem of said needle valve, and a valve-controlled pipe communicating with said plug.

115 2. A fuel conductor terminating in a nozzle, a valve seat in said nozzle, a needle valve provided with a taper ended stem adapted to engage said valve seat, said needle valve having a central bore in communication with said nozzle and a threaded stem provided with a transverse opening 120 into said bore, a hollow plug having a closed end and a transverse threaded opening receiving the threaded and perforated portion of the stem of said needle valve, and a valve-controlled pipe communicating with 125 said plug.

130 3. A burner comprising a cross, a fuel conductor connected to one arm of the cross, a hollow plug having a closed end inserted in the opposite arm of the cross, a nozzle in

another arm of said cross having a valve seat in its inner end, a needle valve, a gland in the arm of the cross opposite the nozzle in which the needle valve rotates, said holder plug having a transverse threaded opening through which the stem of the needle valve is threaded, said needle valve having a bore communicating with said nozzle and a transverse orifice placing said bore in communication with the interior of said plug.

4. The combination of a burner pipe, a fuel conductor having one limb extending from end to end of said burner pipe, and a return limb, both lying in close proximity to the wall of said burner pipe, a looped pipe interposed between said limbs and lying adjacent the rear end of said burner pipe, said return limb terminating in a nozzle directed into the front end of said burner pipe.

5. The combination of a burner pipe, a fuel conductor having a plurality of interconnected loops one limb of which extends along one side of the burner pipe and the other limb along the other side thereof, both in proximity thereto, one limb of said loop terminating in a nozzle directed into the front end of said burner pipe.

6. The combination of a burner pipe, a looped fuel conductor the opposite limbs of which extend on opposite sides of said burner pipe in close proximity thereto, said limbs being connected by a section of increased heating area extending across the rear end of said burner pipe, and a nozzle for directing fuel from said conductor into the front end of said burner pipe.

7. The combination of a burner pipe, a fuel conductor comprising a loop the opposite limbs of which lie on opposite sides of said burner pipe and in close proximity thereto, said limbs being connected across the rear end of said burner pipe by a series of bends arranged in a plane intersecting the axis of said burner pipe, one of said limbs terminating in a nozzle directed into the front end of said burner pipe.

8. The combination of a fuel conductor having a heat absorbing surface said conductor terminating in a nozzle arranged to direct its discharge against said heat absorbing surface, valves for controlling the flow of fuel through said conductor, a pipe communicating with said conductor adjacent the nozzle, and a branched pipe connecting said pipe with said conductor at a point distant from the nozzle.

9. The combination of a fuel conductor having a heat absorbing surface, said conductor terminating in a nozzle arranged to direct its discharge adjacent said heat absorbing surface, a needle valve for controlling the flow of fuel from said nozzle, a pipe adapted to convey an atomizing fluid into said nozzle, means in said pipe for controlling the flow of said atomizing fluid to said nozzle, and a connection between said pipe and a point in said fuel conductor distant from said nozzle and adapted to divert from said pipe through said conductor for cleaning purposes.

In testimony whereof I affix my signature.

JOHN A. BISHOP.
